A. J. Hersey,
BY A. J. Patterson,

ATTORNEY

UNITED STATES PATENT OFFICE.

ARTHUR J. HERSEY, OF DULUTH, MINNESOTA.

SHOE-CALK.

1,053,506.

Specification of Letters Patent. Patented Feb. 18, 1913.

Application filed February 27, 1911. Serial No. 611,098.

To all whom it may concern:

Be it known that I, ARTHUR J. HERSEY, a citizen of the United States, residing at Duluth, in the county of St. Louis and State 5 of Minnesota, have invented certain new and useful Improvements in Shoe-Calks, of which the following is a specification, reference being had therein to the accompanying drawing.

10 My invention relates to improvements in shoe calks, and pertains particularly to those used on baseball shoes.

The object of my invention is to provide a calk of the character described, which will 15 enable the wearer to obtain a firm grip upon the ground to prevent slipping and at the same time to provide a calk in which there are no angular corners, which minimizes the possibility of serious injury in the event of 20 being struck or stepped upon by one wearing said calk.

Another object of my invention is to provide a more simple, cheap and effective calk of this character having certain details of 25 structure hereinafter fully described.

In the accompanying drawings—Figure 1 is a bottom plan view of a shoe showing my improved calk or cleat applied thereto. Fig. 2 is a side elevation of my improved 30 calk. Fig. 3 is an edge view partly broken away and looking in the direction of the arrow, Fig. 1. Fig. 4 is a side elevation of one of the plates showing the notch to receive the other plate and showing the attaching ears. Fig. 5 is a side of the other 35 plate notched to interlock with the plate shown in Fig. 4.

Referring now to the drawing, 1 represents the base-plate upon which are mounted 40 my improved calks 2. The plate is secured to the shoe by means of screws passing through openings 3, in the usual manner. While I have shown three calks on the plate, it will be understood that any number may 45 be used and each calk may have a separate plate or base provided with openings whereby it is attached to the shoe.

The calk is preferably composed of two substantially semi-circular-shaped projections 50 3' and 4, intersecting each other at their centers forming a cross composed of four radially arranged segmental members curving downwardly in the arc of a circle from the center to the plate 1, whereby a 55 calk is provided with continuous curved edges which avoid any sharp corners and

thus avoid any liability of injury by coming in contact therewith. The peripheral edges of the calk may be beveled as indicated at 5, to form a better surface to hold 60 in the ground. These calks are preferably placed upon the sole of the shoe in such a manner that the calking surface of both semi-circular members extends diagonally across the sole of the shoe, so that in the 65 event of striking an object a side blow or direct forward or back blow, two quarters of the calking surface will be impinged in the impact and thus the thrust divided and the danger of abrasion minimized. When 70 used in direct contact with the earth while walking or running, the full benefit of the entire four quarters of the calking surface is utilized, forming an exceedingly effective calk. 75

From the foregoing it will be seen that each half of each semi-circular member forms a guard to the opposite semi-circular member, keeping it from coming in direct contact with an object, and it is also 80 evident that there may be a greater or less number of calking segments such as a three or five pointed cross forming the calk without departing from the invention.

In Figs. 4 and 5 I have shown a convenient manner of interlocking the two members comprising the calk, a portion of the center of each being cut away and designed to fit together one over the other, each having projections 6 which pass 85 through suitable openings in the plate 1 and are riveted thereto. The plate 3', as shown, is provided at the center with the notch 7, which extends about half the length of the plate and is provided at its lower edge with 90 the lugs 6, which extend through the plate 1 and are turned over or riveted to secure it thereto. The plate 4 is likewise provided with the ears or lugs 6 and is provided in its lower edge with a notch 7', which interlocks with the notch 7 of the plate 3', whereby 95 the upper and lower edges of the plates are flush with each other. This provides a more simple, cheap and effective manner 100 of making the calks.

Having thus described my invention, what I claim and desire to secure by Letters Patent is—

1. A device of the character described, comprising a plate, a plurality of calks secured thereto, each calk formed of a plurality of members having curved outer edges 110

intersecting each other and flush, said members so arranged upon the plate that they extend obliquely across the shoe when applied thereto.

5. 2. A device of the character described, comprising a plate, a calk secured thereto and formed of members having lower straight edges and curved flush intersecting edges, and lugs carried by the lower straight edges of said curved members for securing them to said plate.

10. 3. A device of the character described, comprising a plate, a calk formed of interlocking members having their outer edges flush, and lugs carried by the lower edges of said members and extending through openings in the plate for securing the members thereto.

4. A device of the character described, comprising a plate, a calk formed of a member having a curved outer edge having a notch therein and a straight inner edge, a second member having a smooth unbroken outer edge and a straight lower edge provided with a notch adapted to interlock 25 with the notch of the first mentioned member, and said notch in the second member being of such a length that the outer edges of the members are flush, and means for attaching said members to the plate.

In testimony whereof I hereunto affix my signature in the presence of two witnesses.

ARTHUR J. HERSEY.
